Primary Examiner — Sandra Morris(74) *Attorney, Agent, or Firm* — Whitham Curtis Christofferson & Cook, PC(57) **CLAIM**

We claim the ornamental design for pressure washer, as shown and described.

DESCRIPTION

FIG. 1 is a first isometric view of a pressure washer;
FIG. 2 is a second isometric view of the pressure washer;
FIG. 3 is a third isometric view of the pressure washer;
FIG. 4 is a fourth isometric view of the pressure washer;
FIG. 5 is a front elevation view of the pressure washer;
FIG. 6 is a top plan view of the pressure washer;
FIG. 7 is a left side elevation view of the pressure washer;
FIG. 8 is a right side elevation view of the pressure washer;
FIG. 9 is a rear elevation view of the pressure washer; and,
FIG. 10 is a bottom plan view of the pressure washer.
The broken lines illustrate environmental structure and form
no part of the claimed design.
